UNITED STATES PATENT OFFICE.

CHARLES MEHLIN, OF FORT LEE, NEW JERSEY.

PIANO CONSTRUCTION.

Application filed August 3, 1923. Serial No. 655,422.

This invention relates in general to piano construction, and has for its object broadly the increasing or diminishing of the volume of a sustained tone at the will of the player.

5 The invention contemplates the provision in a piano of a sound chamber controllably communicating with the atmosphere and adapted to directly receive and amplify the vibrations of the sound board itself.

10 Another important object of the invention is the provision, along with such a chamber, of easy means for controlling the function of such chamber and this without the use of the hands of the player.

15 A further important object of the invention is the provision of such an arrangement which will require minimum change in standard piano construction.

Numerous other objects and advantages 20 of the invention will be apparent as it is better understood from the following description, which, taken in connection with the accompanying drawings, discloses a preferred embodiment thereof.

25 On the drawings, Figure 1 is a top plan view of a grand piano;

Fig. 2 is a front elevation thereof, the legs being shown broken away;

30 Figs. 3 and 4 are large sections taken substantially on the lines 3—3 and 4—4 of Fig. 1;

Fig. 5 is a section taken substantially on the line 5—5 of Fig. 4;

Fig. 6 is a bottom plan view of the piano body; and

35 Fig. 7 is a section taken substantially on the line 7—7 of Fig. 5.

While for the purpose of illustrating the invention it has been shown as incorporated in a grand piano, it will be readily manifest, 40 as the invention is better understood, that it can with equal facility be employed in pianos of the upright construction.

Referring to the drawings, reference character 11 indicates the piano rim, which is composed in the present instance of an outer rim member 12 and an inner rim member 13 upon the latter of which is mounted the sound board 14. This sound board is fast about its 45 perimeter to the rim and is cut away at 15 to provide a free edge 16 at right angles to the direction of the grain of the sound board and across its longest dimension. A sound 50 chamber is provided beneath the sound board and is defined at the top by the sound board 55 or vibrator itself, at the bottom by a second

board 17 and at the sides by the rim 11 of the piano and the usual rail 18 and sound board supporting block 19 which constitute the cross block. It will be noted that this 60 second board 17 does not extend down as far as the bottom of the rim and, therefore, will in no way interfere with the leg block 18. This second board 17 is cut away at 21 to correspond with the cut away part 15 of the 65 sound board, providing at this point communication with the atmosphere. A closure is provided for this chamber and in the present instance this closure is of vane type located at the opening 15 of the sound board. Three 70 vane members, numbered respectively 22, 23 and 24, are shown on the drawing and each of these is pivoted at 25 in bearings 26 in a bearing block 27 carried by and forming a part of the rim member 13. The three vanes 75 are connected together by a shutter connection 28 so that they may move conjointly and from the closed position shown in full line position in Fig. 7 to that shown in dotted lines. The lower vane member is provided 80 with an arm 29 pivoted to a curved link 31 to a short link 32, in turn connected to one arm 33 of a bell crank pivoted at 34 beneath the second board 17. A spring 35 connected to the link 32 at one end and to a post 36 at 85 the other, pulls the vanes toward closed position and mechanism is provided which is operable by the mere movement of the knee of a player for positively opening the vane closure to the extent and for such periods as 90 may be desired in playing.

This opening or controlling mechanism includes a link 37 extending from the other arm 38 of the bell crank (already mentioned) to an arm 39 of a bell crank fixed beneath 95 the key board or key bottom, the other arm 41 of this last mentioned bell crank is connected by a link 42 with an arm 43 of a lever pivoted at 44 beneath the key board or key bottom and having an end 45 extending out 100 for engagement by a pivoted arm 46 arranged so that the knee of the player may engage the same.

The arm 46 is freely movable in a clockwise direction (viewing Fig. 6) to a position 105 beneath the key board so that it is out of sight when it is not desired to use the sound chamber.

It is thought that the invention and many 110 of its attendant advantages will be understood from the foregoing description, and it will be apparent that various changes may

be made in the form, construction and arrangement of the parts without departing from the spirit and scope of the invention of sacrificing all of its material advantages, 5 the form hereinbefore described being merely a preferred embodiment thereof.

I claim:

1. In a piano, the combination of a sound board having a free edge, a second board therebeneath, piano parts co-operating with both said boards to form a sound chamber, and means located at said free edge for controlling communication between said sound chamber and the atmosphere.
- 10 2. In a piano, the combination of a plurality of sound boards spaced apart and formed with free edges, piano parts co-operating with the sound boards to form a sound chamber and adjustable means for controlling the extent of opening between said sound boards at said free edges.
- 15 3. In a piano, the combination of a sound board having a free edge, piano parts co-operating with said board to form a sound chamber and an adjustable means for providing a controllable opening for said sound chamber at said free edge.
- 20 4. In a piano, the combination of a rim, a sound board mounted therein, a second board beneath said sound board, said sound board and second board forming the upper and bottom members of a sound chamber, and a closure for said chamber pivotally mounted in said rim.
- 25 5. In a piano, the combination of a piano rim, a sound board, a second board mounted therebeneath, said sound board and said second board forming top and bottom members of a sound chamber, a vane closure pivoted in said rim, a key board, a linkage system of links and bell cranks communicating between said closure and said key board, and a member pivoted to the bottom of said key board and adapted, when in one position, to be moved to actuate said linkage and, when in another, to be disposed entirely beneath said key board.
- 30 6. In a piano the combination of a piano rim and sound board supported on one side of said rim, a second board mounted on the other side of said rim, said sound board and said second board forming top and bottom members of a sound chamber and having a free edge, and a vane closure pivoted in said rim between said sound board and said second board, said vane closure being controllable to restrict the sound from the sound chamber.
- 35 7. In a piano the combination of a piano rim and sound board supported on one side of said rim, a second board mounted on the other side of said rim, said sound board and said second board forming top and bottom members of a sound chamber and having a

free edge, and a vane closure pivoted in said rim between the free edges of the sound board 65 and said second board, said vane closure being movable to entirely close said sound chamber.

8. In a piano the combination of an endless piano rim, a sound board secured to one side of said rim and having a free edge, a second board secured to the opposite side of said rim and having a free edge located opposite the free edge of the sound board, said sound board, said rim and said second board forming a sound chamber, and manually controllable means positioned between the free edges of said sound board and said second board for establishing communication between the sound chamber and the atmosphere.

9. In a piano the combination of an endless piano rim, a sound board secured to one side of said rim and having a free edge, a second board secured to the opposite side of said rim and having a free edge located opposite the free edge of the sound board, said sound board, said rim and said second board forming a sound chamber, a plurality of vanes pivoted in the rim and adapted to provide a closure extending between the edges of said sound board and said second board, and means for controlling said vanes to establish communication between the sound chamber and the atmosphere.

10. In a piano the combination of an endless piano rim, a sound board secured to one side of said rim and having a free edge, a second board secured to the opposite side of said rim and having a free edge located opposite the free edge of the sound board, said sound board, said rim and said second board forming a sound chamber, a plurality of vanes pivoted in the rim and adapted to provide a closure extending between the edges of said sound board and said second board, and means for controlling said vanes to establish communication between the sound chamber and the atmosphere, said means including a member pivoted to the bottom of the key board of the piano and extending beyond the edge thereof when in operative position only.

11. In a piano, in combination with the rim and leg block disposed thereunder and the cross block, a sound board disposed at the upper end of said cross block and rim and having a free edge adjacent and spaced from said rim, a second sound board disposed in spaced relation beneath said first sound board, said second sound board being located above the bottom of the rim and above the leg block, said second sound board having a free edge registering with that of the first sound board to provide a sound opening communicating with the atmosphere and communicating with the chamber formed by the spaced sound board.

CHARLES MEHLIN.
